ADVERTISING DEVICE

Charles Horner, Detroit, Mich.

Application May 13, 1933, Serial No. 670,852

6 Claims. (Cl. 40—126)

This invention relates to an advertising device, and more particularly contemplates an advertising device wherein the advertised articles are passed in miniature before the eyes of the observer. This result is achieved by utilizing a conveyer of the endless chain type which is provided with a plurality of independent compartments each of which houses a miniature of the article which is to be advertised and moved past the observer.

This invention further contemplates an advertising device provided with an upper surface upon which a completed article or assembly such as a home or automobile, for example, may be displayed and a traveling lower surface upon which are displayed and passed before the eyes of the observer the various materials and articles from which the house or automobile displayed on the upper surface is made and furnished.

In the drawings:

Fig. 1 is a side elevation of the advertising device.

Fig. 2 is a plan view with the upper surface broken away to show the under structure.

Fig. 3 is a vertical section showing in detail the compartment and conveyer arrangement.

Fig. 4 is a fragmentary front elevation showing the compartment in detail.

Fig. 5 is a fragmentary detail plan view of the conveyer and compartments.

Fig. 6 is a section along the line 6—6 of Fig. 5.

Referring more particularly to the drawings it will be seen that the advertising device comprises two levels, the upper surface or level 1 and the lower surface or sub-level 2. The surface 1 has mounted thereon in miniature an exact reproduction of what in this case, by way of example, is a pair of homes with the surrounding grounds. It is, of course, understood that the surface level 1 can be provided in miniature with other types of buildings and grounds or any other article depending upon what is to be advertised. The lower surface 2 is provided with an endless conveyer upon which is mounted a plurality of compartments for housing various articles or materials which are preferably transported by the conveyer past the eye of the observer to better gain the attention of the observer.

The frame work of the advertising device comprises generally a lower frame work 3 of metal, wood, or any other suitable material. The upper frame work which supports the roof 4, may be similar to the lower frame work 3, and in this

instance comprises a plurality of joists 5 which are secured together in spaced relation by the brace 6 which extends along the longitudinal axis of the roof. The upper frame work is supported by a plurality of studs 7 which are inset somewhat from the outer periphery of the roof 4 to provide an overhanging ledge 8. Mounted on the underside of the roof 4, one between each two successive joists 5, are a plurality of light bulbs 9 for lighting up the traveling conveyer and displays below. These light bulbs preferably extend completely around the periphery of the underside of the roof 4 but, of course, if only one side of the advertising device is to be viewed then lights 9 need be inserted only along that side. It will be noted that the periphery of the roof and upper frame work is provided with a depending rim 10 which completely conceals the bulk from the view of the observer. Hence, the articles which are displayed are illuminated successfully without subjecting the observer to the glare of the light bulbs.

Each of the studs 7 have mounted, in any suitable manner, on the outer face thereof a support bracket 11. These support brackets 11 support a guide member 12 provided with a guideway or guide groove 13. The guide member 12 is in the form of a rim and extends completely around the periphery of the device. The space between the bottom frame 3 and the guide 12 can be closed by any suitable sheathing 14. Mounted in the corner formed by the several brackets 11 and the studs 7 is an angle iron 15 which extends completely around the device to form a track-way for the conveyer chain 16. The angle iron 15 may be secured to the studs 7 and brackets 11 by any suitable means such as the screws 17.

The conveyer is made up of the chain 16 in conjunction with a plurality of separate platforms 18. The outer edge 19 of each of the platforms 18 is guided in the guideway 13 and at the front portion of the inner edge 20 is pivoted as at 21 to a bracket 22 which is riveted or otherwise suitably fixed to the chain 16. The top and bottom faces of each of the platforms 18 are guided along the rear portion of the inner edge 20 between the brackets 23 but are not pivoted to the brackets 23. The bracket 23 is riveted to the chain 16. The bracket 23 comprises a pair of fingers 41 which overlap and slidably engage the top and bottom faces of the platform 18 and thereby serve as a locating device to keep the platform 18 in the plane of the chain and the guideway 13 and in turn permit the platform 18

to move in and out radially as the platform swings around the semi-circular or curved end portion of the track-way formed by the angle iron and guideway 13.

5 As shown in Fig. 5, upon reaching the semi-circular end 24 of the track-way the forward portion of the inner edge 20 of the platform 18, being pivoted to the brackets 22, follows the chain as it goes around the bend thus throwing 10 the rear portion of the platform 18 radially outward. Since the bracket 23 is not pivoted to the platform 18 this in and out radial movement is permitted, the bracket serving as a guide. To 15 accommodate this radially outward movement at the curved ends of the track-way the guideway 13 is deepened as at 25. The chain 16 is driven by a sprocket 26 which in turn preferably is driven by an electric motor 27. Opposite the sprocket 26 the guideway is provided with a pair 20 of thrust rollers 28.

To properly maintain the chain 16 in position as it travels about the curved ends 24 the angle iron 15 is provided with a rail 38 which, as shown in Fig. 6, provides a track upon which the rollers 39 of the chain 16 travel and the top and bottom links 40 of the chain overlap the top and bottom faces of the track 38 which prevents the chain from jumping the track and getting out of position as it travels about the curved ends of the 30 track-way.

35 Each of the platforms 18 has fixed thereon a block 29 provided with a flat upper face 30 which serves as a floor for the compartment and a beveled outer edge 31 upon which the trade name or description of the article displayed is marked. The block 29 has fixed thereto the two side walls 32 and the rear wall 33. The front of the compartment is open and the roof is likewise open to permit illumination by the light bulbs 9. As 40 shown, each of the individual display compartments are formed by the block 29, the side walls 32 and the rear wall 33. In each of these compartments is displayed for advertising purposes in miniature any article which it is desired to advertise. As shown in Fig. 1, one of the compartments has displayed therein in miniature an electric refrigerator 34, another a boiler 35, another has a miniature display of brick 36, and still another plumbing fixtures 37.

50 In operation the motor, through the sprocket 26, causes the chain 16 and associated platforms 18 to travel about the periphery of the display devices guided in the guideways 13 and on the angle iron 15. As the conveyer travels its course 55 the compartments with their open fronts present to the eye of the observer in miniature the various articles illuminated from above. The specific trade name or description of either of the articles being marked upon the inclined face 31 60 of the block 29, it can be readily read by the observer.

Hence, it will be seen that this advertising device passes before the eye of the observer in miniature the advertised articles. As herein shown 65 and described the various articles which are displayed in the compartments are the materials and household utilities from which the model homes displayed on the roof 4 are made and furnished. This same idea, of course, can be carried out with numerous finished articles, the completed article or assembly being shown on 70 the upper surface 1 and the various articles or component parts from which the completed article or assembly is fabricated or furnished can 75 be displayed and advertised individually in the

several traveling compartments of the lower surface 2.

Each platform 18 is provided with a heel 42 which projects into the notched corner 43 of the platform immediately in front. It is the purpose of the heels 42 to keep the platforms 18 and their respective compartments in line on the straightaway otherwise, the platforms being pivoted at the forward part of their inner edge only, would swing inwardly against the chain on the 10 straightaway. 5

I claim:

1. An advertising device comprising in combination an upper surface, a support for the upper surface, the upper surface extending beyond the said support to form an overhanging peripheral portion, a conveyer positioned below the overhanging portion of the upper surface comprising an endless chain and a plurality of independent platforms pivotally connected to the chain at the forward part of their inner edge, a continuous guideway for guiding the said platforms along their outer edges, a compartment for each of the said platforms having side and rear walls and an open top and front, the said compartments being positioned beneath the overhanging portion of the upper surface which serves as a cover for the same, and means for moving the said chain and associated platforms and compartments along their guideways about the periphery of the 20 upper surface. 25

2. An advertising device comprising in combination an upper surface, a support for the upper surface, the upper surface extending beyond the said support to form an overhanging peripheral portion, a depending rim for the periphery of the upper surface, a conveyer positioned below an overhanging portion of the upper surface comprising an endless chain and a plurality of independent platforms pivotally connected to the chain at the forward part of their inner edge, a continuous guideway for guiding the said platforms along their outer edges, a compartment for each of the said platforms having side and rear walls and an open top and front, the said compartments being positioned beneath the overhanging portion of the upper surface which serves as a cover for the same, lighting means positioned beneath the upper surface inside the depending rim and above the said compartments 50 for illuminating the same, and means for moving the said chain and associated platforms and compartments along their guideways about the periphery of the upper surface. 55

3. An advertising device comprising in combination a pair of parallel guideways forming a closed circuit, a portion of the circuit being curved, an endless chain co-extensive with the guideways and arranged to travel around the closed circuit including the curved portion, a plurality of independent platforms pivotally connected to the chain at the forward part of their inner edge, a pair of guide fingers fixed to the chain to the rear of each pivot and overlapping the top and bottom faces of the said platform along the rear portion of the inner edge for guiding the rear portion of the platform in its in and out movement as it travels about the curved portion of the guideways. 60 65

4. A device for displaying articles comprising in combination continuous guideways forming a closed circuit, a plurality of independent platforms guided by the said guideways, an endless chain for moving the platforms along the guideways, each platform having a pivotal connection 70 75

with the chain at the forward part of its inner edge, and a stop at the forward part of the inner edge of each platform for engagement with the rear part of the inner edge of the adjacent platform to prevent the adjacent platform from swinging about its pivot inwardly against the chain.

5. A device for displaying articles comprising in combination continuous guideways forming a closed circuit, a plurality of independent platforms guided by the said guideways, an endless chain for moving the platforms along the guideways, each platform having a pivotal connection with the chain at the forward part of its inner edge, each platform having a heel projecting from its forward inner edge ahead of the pivot and a notch at its rear inner edge, the heel of one platform engaging the next adjacent plat-

form in the notch to prevent the next adjacent platform from swinging inwardly against the chain.

6. An advertising device comprising in combination a pair of parallel guideways forming a closed circuit, a portion of the circuit being curved, an endless chain co-extensive with the guideways and arranged to travel around the closed circuit including the curved portion, a plurality of independent platforms guided by said guideways, each platform having a pivotal connection with the chain at the forward part of its inner edge whereby each platform upon reaching the curved portion of the guideway swings about its pivot away from the platform immediately following.

CHARLES HORNER.
